(57) **CLAIM**

The ornamental design for a cordless power supply, as shown and described.

DESCRIPTION

FIG. 1 is a front perspective view of a cordless power supply showing our new design;
FIG. 2 is a left side elevation view thereof;
FIG. 3 is a right side elevation view thereof;
FIG. 4 is a top plan view thereof;
FIG. 5 is a bottom plan view thereof;
FIG. 6 is a front elevation view thereof;
FIG. 7 is a rear elevation view thereof;
FIG. 8 is a front perspective view of a second embodiment of a cordless power supply showing our new design;
FIG. 9 is a left side elevation view thereof;
FIG. 10 is a right side elevation view thereof;
FIG. 11 is a top plan view thereof;
FIG. 12 is a bottom plan view thereof;
FIG. 13 is a front elevation view thereof;
FIG. 14 is a rear elevation view thereof;
FIG. 15 is a front perspective view of a third embodiment of a cordless power supply showing our new design;
FIG. 16 is a left side elevation view thereof;
FIG. 17 is a right side elevation view thereof;
FIG. 18 is a top plan view thereof;
FIG. 19 is a bottom plan view thereof;
FIG. 20 is a front elevation view thereof;
FIG. 21 is a rear elevation view thereof;
FIG. 22 is a front perspective view of a fourth embodiment of a cordless power supply showing our new design;
FIG. 23 is a left side elevation view thereof;
FIG. 24 is a right side elevation view thereof;
FIG. 25 is a top plan view thereof;
FIG. 26 is a bottom plan view thereof;
FIG. 27 is a front elevation view thereof;
FIG. 28 is a rear elevation view thereof;
FIG. 29 is a front perspective view of a fifth embodiment of a cordless power supply showing our new design;
FIG. 30 is a left side elevation view thereof;
FIG. 31 is a right side elevation view thereof;
FIG. 32 is a top plan view thereof;
FIG. 33 is a bottom plan view thereof;
FIG. 34 is a front elevation view thereof; and,
FIG. 35 is a rear elevation view thereof.
The broken lines shown represent unclaimed subject matter and form no part of the claimed design.
